Primary Examiner — Calvin E Vansant*Assistant Examiner* — Mark T. Philipp(74) *Attorney, Agent, or Firm* — QuickPatents; Kevin Prince(57) **CLAIM**

The ornamental design for a dual-cylinder air compressor, as shown and described.

DESCRIPTION

FIG. 1 is a top perspective view of a dual-cylinder air compressor, showing our new design;

FIG. 2 is a bottom perspective view thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a left-side elevational view thereof, the right-side elevational view being a mirror image thereof.

The broken lines in the figures depict portions of the dual-cylinder air compressor that form no part of the claimed design.
